[57] CLAIM

The ornamental design for fencing section, as shown and described.

DESCRIPTION

FIG. 1 is a rear elevational view of two adjacent panels of a fencing section showing my new design;

FIG. 2 is a front elevational view thereof;

FIG. 3 is a top plan view thereof;

FIG. 4 is a view from one end of FIG. 1, the view from the other end of FIG. 1 being identical;

FIG. 5 is a cross section taken on the line V—V of FIG. 2; and

FIG. 6 is a cross section taken on the line VI—VI of FIG. 2.

FIG.1.

FIG.2.

FIG.3.

FIG. 4.

FIG. 5.

FIG. 6.
